UNITED STATES PATENT OFFICE.

HERBERT E. GUSTAFSON, OF PUEBLO, COLORADO.

MINIATURE ELECTRIC LAMP.

1,105,770.

Specification of Letters Patent.

Patented Aug. 4, 1914.

Application filed February 25, 1914. Serial No. 820,924.

To all whom it may concern:

Be it known that I, HERBERT E. GUSTAFSON, a citizen of the United States, and a resident of Pueblo, in the county of Pueblo 5 and State of Colorado, have invented a certain new and useful Improvement in Miniature Electric Lamps, of which the following is a full, clear, and exact description.

My invention is an improvement in incandescent electric lights and relates in particular to the provision of a miniature or low candle-power light adapted to be placed within a phonograph or "talking machine."

The principal objects of my invention are the provision of a lamp, mounting and shade which may be placed on the inner side of the cover, or elsewhere within the case of the device, without making it necessary to provide a cord opening through the cover or side of the case; and which will not only be useful in illuminating the disk platen but which will also serve to enhance the appearance of the entire device. To these ends I have provided novel combined socket and shade brackets which will permit of the lamp cord leaving the socket and bracket in a direction at right angles to the axis of the lamp, and which will enable the lamp to be attached to the instrument case by a single screw in the direction of the axis of the lamp and which screw will be hidden by the socket when in place.

In the two sheets of drawings accompanying this application and forming a part thereof Figure 1 is a perspective view of one form of my device, showing the lamp, bracket and shade as seen from the front or open side of the shade; Fig. 2 is a perspective, on a larger scale, of the bracket shown in Fig. 1; Fig. 3 is a perspective of the cover and a portion of the box of a phonograph, illustrating the preferred location for the lamp; Fig. 4 is an enlarged sectional view of the lamp socket; and Fig. 5 is a perspective view of a slightly modified form of bracket, with which is combined a protecting and insulating tube for the wires.

Referring to the drawings, and more particularly to Sheet 1, 5 indicates an ordinary incandescent bulb of low candle-power and 5 a socket into which the bulb screws by engagement with the interior threads 7. This socket, shown in section in Fig. 4, comprises an outer casing of insulating material 8, a porcelain insulating head 9 through which passes the pole 11 (the other pole being

formed by the threaded copper sleeve 7), and a pair of wires 12, 13, connected to the two poles. These wires pass out of the socket through an opening 14 in one side 60 thereof and an insulating head 10 closes the end of the socket, completely insulating the inclosed wires from the rear.

One form of combined socket and shade holding bracket is shown in Fig. 2. It comprises a split sleeve 15 for the reception of the socket 6, which snugly fits therein, a bottom lug 16 perforated at 17 for the reception of an attaching screw, and a side lug 18, also perforated, for attachment of the shade 70 19. This shade is preferably semi-ovate in shape and, on account of the added effect, I prefer to make it out of translucent shell, such as abalone or the like, the slight amount of colored light passing through the shade 75 being insufficient to annoy one looking in that direction but, on the contrary, producing a very pleasant effect—particularly when the case is of rich wood, such as mahogany.

Fig. 3 shows the preferred location of the light when placed on a "Victrola"—on the under side of the cover with the shade turned toward the front, the bracket being attached by means of a screw passing 85 through the opening 17. When so placed the cords 12, 13, may be carried down the cover to the box and passed out through a small hole in the bottom or rear of the case. It will be obvious that the lamp may also be 90 placed in other positions—as, for instance, upright within the box near the front. It will also be obvious that the lamp may be employed in other places than here described without departing from my invention.

In many localities the wiring regulations prohibit the running of wires along a wood surface and also the flexing of open wires such as would take place where the cover and box meet each time the cover is 100 raised or lowered. To meet these regulations I have designed the form shown in Fig. 5, in which the wires as they pass down the flat upper portion of the cover are inclosed in a metallic tube 20. A bend 21 is 105 provided in the tube 20 adjacent the point where the "swell" 22 of the cover begins (Fig. 3); and from there on to a point well within the box the wires 12, 13, are incased in an insulated, flexible, metallic tube 23. 110 The tube 20 carries at its upper end (preferably integral therewith) a split sleeve 15^a

for holding the socket 6 and a lug 18^a perforated in two places for receiving the attaching screw and the means for securing the shade 19 respectively.

5 Having thus described my invention, what I claim and desire to secure by Letters Patent is:

- 10 1. A bracket for an electric light comprising a sleeve having a lateral opening therein and a supporting lug extending across one end of said sleeve and adapted to receive attaching means in the direction of the axis thereof.
- 15 2. A bracket for an electric light comprising a sleeve having a lateral opening therein, a supporting lug extending across one end of said sleeve and adapted to receive attaching means in the direction of the axis of the sleeve, and shade supporting means.
- 20 3. A bracket for an electric light comprising a resilient split sleeve, a supporting lug extending across one end of said sleeve and adapted to receive attaching means in the direction of the axis of the sleeve, and shade supporting means.
- 25 4. A bracket for an electric light comprising an insulating tube, a resilient split sleeve formed as a continuation thereof, and

a lug also carried by said tube and extending across one end of said split sleeve, said lug having a perforation therein adapted to receive an attaching screw in the direction of the axis of the sleeve and a perforation for receiving means for securing a shade thereto.

35 5. An incandescent electric lamp socket comprising an insulating casing, a pair of poles within said casing adapted to coöperate with a bulb, and a pair of wires connected to said poles respectively, said casing having an opening in its side whereby said wires may pass out above the base of said socket and in a direction at right angles to the axis thereof, in combination with a supporting bracket for said socket having means in the line of the axis of said socket for attaching said bracket to a supporting surface and a lateral opening therein through which said wires may pass.

40 In testimony whereof I have hereunto affixed my signature in the presence of two witnesses.

45 HERBERT E. GUSTAFSON.
